UNITED STATES PATENT OFFICE.

RUDOLF HÖFLER, OF WIENER-NEUSTADT, AUSTRIA.

SPINNING TOY.

Application filed October 17, 1922. Serial No. 595,138.

To all whom it may concern:

Be it known that I, RUDOLF HÖFLER, a subject of the Republic of Austria, and residing at Wiener-Neustadt, in the Province of Lower-Austria, Austria, have invented certain new and useful Improvements in a Spinning Toy, of which the following is a specification.

This invention relates to a spinning toy whose top spins about a horizontal axis, which axis operates on an inclined guide.

The invention consists in the construction, combination and arrangement of devices hereinafter described and claimed.

15 The drawing shows by way of example one mode of carrying out the present invention. Fig. 1 is a longitudinal sectional view of the toy, Fig. 2 a plan view of the same, and Fig. 3 a section on the line a—a 20 of Fig. 1.

The toy may be made of any convenient material and may be taken to pieces. It consists of two base-rods 1, whose ends are connected with one another by means of 25 transverse walls 2 and 3. The rods 1 pass through lateral recesses formed in the transverse walls 2 and 3 and are secured to the latter by means of two screw-bolts 4, thus forming a rigid frame. Each base-rod 1 30 is provided at one end with a groove 5 for the reception of a horizontal plate 6, bridging the space between the two base-rods, and the plate 6 is marked with nine spaces 7 for skittles or nine pins 8. By means of 35 pins 10, side-plates 9 are removably secured to the base-rods 1, the said plates forming the lateral borders of the plate 6. The ends of the side-plates rest against the transverse wall 2 and are of the same height as the 40 latter. The transverse wall 3 is higher than the wall 2 and is provided at both sides with a vertically adjustable bearing 11 which is open at the top. Similar bearings 12 are also arranged at the outside of the side- 45 plates 9. Rods 13 of circular cross-section pass through the bearings 11 and 12 which are of different height, the said rods being adjustable in longitudinal direction and in the present case not rotatable. For this 50 object the rods 13 are provided with a longitudinally extending groove or slot 14, in which pins 15 secured to the side-plates 9 engage and are slideable. The two rods 13 serve as bearing and guide for a top 16, 55 which consists of a metal disc of suitable weight, centrally secured to a bar 17 of

circular cross-section. The round bar 17 serving as the axis of the top is considerably longer than the distance between the rods 13 and is provided at each end with a ball 60 18, which serves as grip for actuating the top 16. By means of pins 20, a number of blocks 19 are removably secured to the base-rods 1, each of the said blocks being provided with a groove 21 for the reception of 65 transverse rails 22. The latter rest loosely in the grooves 21 of each pair of blocks 19 and are provided at one or both of its narrow sides with depressions or slots 23 of different width, through which the top 16 70 may pass. A plate 24 furnished with serrations 25 is secured to the top of the wall 2 and serves for engaging the top 16. As already mentioned, each toy is provided with nine skittles or balls, the latter may be 75 deposited in depressions formed in the plate 6.

In play, the top 16 will run down the inclined rods 13 and thereby be guided in the desired manner by an adjustment of the 80 rods 13, so that the top passes through the similarly or differently adjusted depressions 23 of the obstacle rails 22 and finally knock down the skittles. On removing the obstacle rails 22 an ordinary game of skittles may be 85 played and when removing also the skittles a target game or a game at goal may be played. In the latter case the top 16 has to be guided in such a manner, that it will run into any of the serrations 25 of the 90 plate 24. In order to increase the skill required of the player for guiding the top so as to knock down the skittles or to run into any of the serrations 25, the side-plates 9 are used as the running-faces of the top, 95 so that the latter has to be correctly guided before it will reach the side-plates 9.

The incline of the rods 13 may be varied, as desired, by adjusting the position of the toy. For instance they may be brought into a horizontal or such an inclined position that the top has to run up an incline. When rotating the top too fast, the same may be braked or stopped at one of the guide-rods 13.

I claim:

1. In a toy a pair of guide rails spaced apart, a spinning member having a horizontal axle to operate on the guide rails, and an obstacle member arranged in the path of the spinning member, having means to clear the latter, said obstacle member being 110 115

adjustable transversely with respect to the guide rails.

2. In a toy a pair of guide rails spaced apart, a spinning member having a horizontal axle to operate on the guide rails, and an obstacle member arranged in the path of the spinning member, having means to clear the latter, said obstacle member being adjustable transversely with respect to the guide rails, and means to adjustably and detachably mount said obstacle member.

3. In a toy, a base frame, a plate at one end of said frame, game pieces on said plate, said plate and said game pieces having means to detachably position the game pieces on the plate, guide rails, supports

therefor rising from the base frame, and a spinning member having an axle arranged to bear and run on the guide rails.

4. In a toy, a base frame, a plate at one end of said frame, game pieces on said plate, said plate and said game pieces having means to detachably position the game pieces on the plate, guide rails, supports therefor rising from the base frame, a spinning member having an axle arranged to bear and run on the guide rails, and means to detachably secure said plate to said base frame.

In testimony whereof I affix my signature,

RUDOLF HÖFLER.
